UNITED STATES PATENT OFFICE.

NELSON B. ST. JOHN, OF OAKLAND, CALIFORNIA.

DESIGN FOR A TARGET TOY.

Application filed June 15, 1925. Serial No. 13,790. Term of patent 7 years.

To all whom it may concern:

Be it known that I, NELSON B. ST. JOHN, a citizen of the United States, and a resident of the city of Oakland, county of Alameda, State of California, have invented a new, original, and ornamental Design for a Target Toy, of which the following is a specification, reference being had to the accompanying drawings, forming part thereof.

I claim:

The ornamental design for a target toy substantially as shown.

NELSON B. ST. JOHN.
